Les Attorney:

UNITED STATES PATENT OFFICE.

SAMUEL C. MAY, OF MODESTO, CALIFORNIA.

LADY'S HAT-FASTENER.

1,078,793.

Specification of Letters Patent. Patented Nov. 18, 1913.

Application filed November 13, 1912. Serial No. 731,295.

To all whom it may concern:

Be it known that I, SAMUEL C. MAY, a citizen of the United States, residing at Modesto, in the county of Stanislaus and State of California, have invented a new and useful Lady's Hat-Fastener; and I do hereby declare the following to be a full, clear, and exact description of the invention, such as will enable others skilled in the art to 10 which it appertains to make and use the same.

This invention relates to a new and useful lady's hat fastener, the object of the invention being to provide a device of this nature, 15 which is simple, durable, light, efficient and practical in construction, and easily mounted in the hat crown, as well as being simple to operate.

There are disclosed in the drawings certain features of construction, but in practical fields these features may necessitate alterations, to which the patentee is entitled, provided the alterations are comprehended within the scope of what is claimed.

25 The invention comprises further features and combination of parts, as hereinafter set forth, shown in the drawings and claimed.

In the drawings:—Figure 1 is a view of a lady's head, showing a hat in section, with 30 the improved fastener applied. Fig. 2 is a cross sectional view of the hat. Fig. 3 is an enlarged perspective view of the fastener removed. Fig. 4 is a sectional view on line 4—4 of Fig. 3. Fig. 5 is a sectional view on line 5—5 of Fig. 2.

Referring to the drawings more especially 1' designates a stationary jaw, which comprises the usual arched comb 2. This stationary jaw also includes the arms 4, which 40 extend downwardly and rearwardly. The upper forward ends of the arm, are bent at angles as shown, and from one side of each of said bent portions a flange 6 is provided, which under-laps the comb. The other side 45 or edge of each bent portion is provided with a series of fingers 5, which fingers are bent between the teeth of the comb, and lapped under the rib 1', thereby securely attaching said arms to the comb. Said arms are provided with threaded apertures 6^a to receive the shanks 7 of the ornamental buttons 8. In the present case these buttons are diamond shaped, and are designed to act as trimming for the hat. However, their shape

and ornamentation may vary, in constructing the hat fastener in great numbers. The buttons may be covered, if desired, of the same material from which the hat is made. Nuts 9 are threaded upon the shanks of the buttons, in order to hold the arms and the stationary comb jaw in place. Pivoted at the rear ends of said arms are links 11, their upper ends terminating in bent portions, which are provided with the under turned flanges 13^a and fingers 13. These flanges and 65 fingers 13^a and 13 are designed to perform the same functions as those of the flanges and fingers 6 and 5, namely, to underlap the rib 14^a of the comb 14. One of the objects of the invention, is that in manufacturing 70 this improved hat fastener the usual stock tortoise shell arched or other makes of combs are to be utilized, and to which combs the arms 4 and links 11 are to be connected, as in the manner shown in the drawings. In this 75 manner of constructing the device, the cost of production is considerably lessened, owing to the fact that an especially constructed comb is not necessary, as in other devices of this nature. Furthermore, by means of the 80 said flanges 6 and 13^a, and the fingers 5 and 13, the arms and links 11 are firmly secured to said combs. The comb 14 and the links 11 constitute the movable jaw.

Upon each side of the fastener a coil 85 spring 15 is arranged. One end of each spring is connected to one of the links, while the other end is connected at 16 to the forward upper ends of said arm.

Secured in an aperture of the movable 90 comb jaw is a link 16^a, to which a chain or the like 17 having a button 18 is connected. When the comb jaw is closed, so as to co-operate with the other comb jaw, in order to clamp the wearer's hair, the chain is 95 drawn taut, and the button is held closely in contact with the hat. Said button 18 is designed to act as a trimming, rosette or the like for the hat, as are the buttons 8. When it is desired to detach or remove the hat, the 100 wearer should take hold of the button and pull upon the chain in order to open the movable jaw, after which by slightly moving the hat forwardly and upwardly, the same may be removed. The arms and the 105 links may be constructed of any suitable light material, such as aluminum or the like.

From the foregoing it will be noted that

2
there has been devised a simple and efficient
hat fastener, and one which has been found
desirable and practicable.

The invention having been set forth, what
5 is claimed as new and useful is:—

In combination, a pair of slightly curved
combs with the teeth opposed and adapted
to intermesh, one of said combs constituting
10 a stationary jaw, while the other comb con-
stitutes a movable jaw, downwardly and
rearwardly extending arms, their upper and
forward ends terminating in plates extend-
ing substantially laterally and toward one
15 another engaging the body of the stationary
comb jaw and having fingers extending
about and underlying the body of the sta-
tionary comb jaw, said fingers arranged be-
tween the teeth of the stationary comb jaw,
one edge of each plate of each arm having a
20 flange underlying the body of the stationary
comb jaw, downwardly extending links hav-
ing their lower ends pivoted to the rear

lower ends of said arms, the upper ends of
said links terminating in plates extending
substantially laterally and toward one an-
other and engaging the body of the movable
25 comb jaw, one edge of each plate of each
link having a flange underlapping the body
of the movable comb jaw, while the oppo-
site edge of each plate of each link is pro-
30 vided with fingers extending between the
teeth of the movable comb jaw and underly-
ing the body thereof, spring connections be-
tween the links and said arms, and a device
constituting means whereby the movable 35
comb jaw may be opened.

In testimony whereof I have signed my
name to this specification in the presence of
two subscribing witnesses.
